UNITED STATES PATENT OFFICE.

WILLIAM A. HOWARD, OF DIXON, ASSIGNOR OF ONE-HALF TO WILLIAM M. BERNARD, OF ELLIOTT, CALIFORNIA.

EVENER-HINGE FOR HARROWS.

SPECIFICATION forming part of Letters Patent No. 268,898, dated December 12, 1882.

Application filed May 9, 1882. (No model.)

To all whom it may concern:

Be it known that I, WILLIAM A. HOWARD, of Dixon, county of Solano, State of California, have invented an Improved Evener-Hinge for Harrows; and I hereby declare the following to be a full, clear, and exact description thereof.

My invention relates to a new and useful evener-hinge, which is especially adapted for section-harrows; and it consists in certain precise details of construction, as hereinafter fully described, and particularly pointed out in the claim.

The object of my invention is to furnish a connection between the evener and any number of independent sections of a harrow, whereby each section may vibrate freely without the employment of side hinges, and at the same time each may be readily raised to be cleaned without interfering with the others.

Harrows are usually constructed of a number of sections independent of each other to a certain extent. The evener is usually clipped by links to the front center of each section. If this were the only connection, each section would have too great play, and its vibration as it dragged along over clods, &c., would frequently be so great as to cause damage to the other sections. To provide for this a link-connection of various descriptions is made between two sections along their adjoining sides. This keeps each to a limit of vibration, but is objectionable from the fact that it not only limits side movement, but end movement as well, and thereby prevents the section from being raised to be cleaned, as it requires considerable strength to raise the whole harrow. My invention limits the side movement of the sections, and yet allows each to be raised independently of the others.

Referring to the accompanying drawings, Figure 1 shows the application of my device

to sectional harrows. Fig. 2 is an enlarged view of the evener-hinge.

Let A represent one section of a harrow, 45 and B another section, the two lying side by side, as shown. To the front of each section, at its ends, are bolted the links C. These are curved, as shown, in a semi-elliptical curve, the ellipse being divided through its greatest 50 length. D represents the evener. At its ends and toward its middle, opposite to the links C, are bolted clips E. These clips consist of an open frame, in the rear end of which is vertically journaled a roller or spool, e. Before the 55 clips E are bolted to the evener the curved links are fitted through and draw against the spools e. This connection forms a hinge which allows all the side movement or play of the sections which is necessary, and enables me to 60 dispense with side hinges. They can easily vibrate; but because of the hinges being at the ends of the front they are prevented from swinging too freely. Having no side hinges, each section may be raised independently of 65 the others. The rollers e reduce the friction and keep the links and clips from wearing out. They allow the curved links to move from side to side readily, and the open frame of the clip allows them to rise or fall.

Having thus described my invention, what I claim as new, and desire to secure by Letters Patent, is—

The harrow-sections and curved semi-elliptical links C, bolted thereto, in combination with the clips E, bolted to the evener-bar and provided with rollers e, against which links C bear, all constructed, arranged, and operated as set forth.

In witness whereof I hereto set my hand.

WILLIAM A. HOWARD.
